CLAIM

The ornamental design for a display panel or portion thereof with an animated graphical user interface, substantially as shown and described.

DESCRIPTION

FIG. 1 is a front view of a display panel or portion thereof with an animated graphical user interface showing the first image in a sequence of our new design.

FIG. 2 is a second image thereof.

FIG. 3 is a third image thereof.

FIG. 4 is a fourth image thereof; and,

FIG. 5 is a fifth image thereof.

The appearance of the animated graphical user interface sequentially transitions between the images shown in FIGS. 1-5. The process or period in which one image transitions to another image forms no part of the claimed design.

In the figures, the outmost broken line rectangle illustrates a display panel or portion thereof. The remaining broken lines illustrate portions of the graphical user interface. None of the broken lines form part of the claimed design.
